UNITED STATES PATENT OFFICE.

JAMES F. BROWN, OF NEW YORK, N. Y.

PUZZLE.

No. 905,839.

Specification of Letters Patent.

Patented Dec. 8, 1908.

Application filed June 28, 1907. Serial No. 381,205.

To all whom it may concern:

Be it known that I, JAMES F. BROWN, a citizen of the United States, residing in New York city, borough of Manhattan, State of New York, have invented certain new and useful Improvements in Puzzles; and I do declare the following to be a full, clear, and exact description of my invention.

My invention relates to puzzles in which freely moving objects may be moved into a predetermined place by the skill of the operator, and I have provided therein certain novel features to render the operation of the game more difficult.

Referring to the accompanying drawings illustrating my novel puzzle, Figure 1 is a plan view of the preferred form, Fig. 2 is an elevation of the cross-section through the middle of Fig. 1, Fig. 3 is an elevation of the cross-section also through the middle of Fig. 1, but at right angles to the cross-section shown in Fig. 2, Fig. 4 is a plan view of a modification of Fig. 1, and Fig. 5 is an elevation of the cross-section through the middle of Fig. 4.

In Figs. 1, 2 and 3, 1 is a round casing of any suitable material, as, for instance, cardboard or the like, which may or may not be disposed in a square box shown in dotted lines in Fig. 1. Within box or casting 1 a tilting table 4 is pivotally mounted by pivots 2-2 fastened at opposite points on the table and supported by supports 3-3 fixed on the walls of casing 1 at opposite points. On table 4 is disposed a fence 5 inclosing an inner portion of suitable size of table 4. Fence 5 is provided with two gates 6 preferably located on opposite sides. The annular space 8, formed by fence 5 and the vertical wall of casing 1, is adapted to receive freely moving objects, preferably balls 7, of substantial weight and of suitable size to pass freely through gates 6 of fence 5 and of suitable size so as not to fall through the space left between table 4 and the vertical wall of casing 1 for mechanical reasons.

The operation of the puzzle is as follows: The balls 7 are placed into the annular space 8, as shown in Fig. 3. It is evident that in doing so, table 4 will be tilted to one side through the weight of the balls so that its downward tilted side will rest at the bottom of casing 1. It is the object of the operator to cause the balls 7 to roll into the inner portion 9 of table 4 inclosed by fence 5

through either one of gates 6. This may be accomplished by tilting casing 1 by hand to bring table 4 into a horizontal position to start the balls 7 rolling. It is obvious that by these manipulations some of the balls still in the annular space or some of the balls brought already into the inclosure 9 will unexpectedly roll to one side of the table, tilting the same downward on that side if sufficient in number to counter-balance the weight of the other balls remaining on the other side, thus causing the latter balls also to roll over to the tilted side of the table and upsetting the manipulations of the operator to get the rest of the balls from the annular space into the inclosure. It may also happen that some of the balls already in the inclosure 9 will roll out again through one of the gates 6 when the operator tends to get the rest of the balls from the annular space into the inclosure.

In Fig. 1 the gates 6 are shown in line with the pivots 2-2. I have now provided two other pivots 10-10 in opposite sides of table 4 at right angles to pivots 2-2, so that if pivots 2-2 are lifted out of the supports 3-3 pivots 10-10 may be inserted into these supports and thus the table 4 will tilt on a line at right angles to the tilting line of Fig. 1, which renders the puzzle somewhat easier. To render the puzzle more difficult, I have also provided a pivot pin 11 fixed in the center of the bottom of casing 1 and supporting table 4 at its center when lifted from brackets 3 and turned so that neither of pivots 2-2 or 10-10 will be supported by brackets 3. It will be seen that table 4 is now adapted to tilt in all directions, which will render the manipulating of the balls from space 8 into space 9 most difficult. To render the manipulation of the puzzle still more difficult, the outer edge of table 4 near the vertical wall of casing 1 may be chamfered, as shown in Fig. 5 at 12, so that the balls tend to be guided by the groove thus formed, out of which they must be shaken in order to be free to roll through one of the gates 6, which will generally start all the balls rolling to one side and unexpectedly tilt the table. The same purpose may be obtained by having the space between table 4 and the vertical wall of casing 1 large enough to act as a guide-groove for the balls.

In Fig. 4 I have shown a modification of the puzzle shown in Fig. 1. In this modifi-

cation table 4 is of square shape and mounted in a square box 1.

While I have shown in the drawings particular preferred forms of my puzzle, I do not 5 wish to limit myself to these forms, as the purpose may be obtained by any other form or any other manner of pivoting the table; for instance, by having any number of pivots on opposite sides of the table in Fig. 1 so 10 that the table may be tilted in any particular line relatively to the line through the gates. Furthermore, any desired number of gates may be provided in fence 5.

What I claim is:

15 1. In a puzzle, the combination of a casing, a tilting table mounted in said casing, a fence on said table inclosing an inner portion and having an opening, objects adapted to move freely on said table and to pass through said 20 opening, a plurality of pairs of pivots on said table differently located relatively to the opening permitting said table to tilt in different directions respectively relatively to the opening, and means for holding and supporting either of said pairs of pivots selectively. 25

2. In a puzzle, the combination of a casing, a tilting table mounted in said casing, a fence on said table inclosing an inner portion and having openings on opposite sides, objects 30 adapted to move freely on said table and to pass through said openings, said table having a plurality of pairs of pivots and bearings adapted to selectively receive and support either pair of said pivots.

35 3. In a puzzle, the combination of a casing, a tilting table mounted in said casing, a fence on said table inclosing an inner portion and having an opening and objects adapted to move freely on said table and to pass through 40 said opening, a plurality of pairs of pivots on said table, each of said pairs differently located relatively to the opening, a pair of bearings adapted to receive and support either of said pairs of pivots and a single 45 pivot support for said table permitting same to tilt in any direction, said table adapted to be supported either by one of said pairs of bearings or by said single support at will.

4. In a puzzle, the combination of a casing, 50 a tilting table mounted in said casing, a fence on said table inclosing an inner portion and having openings on opposite sides and objects adapted to move freely on said table and to pass through said opening, a plurality 55 of pairs of pivots on said table, each of said pairs differently located relatively to the opening, a pair of bearings adapted to receive and support either of said pairs of pivots and a single pivot support for said table 60 permitting same to tilt in any direction, said table adapted to be supported either by one of said pairs of bearings or by said single support at will.

5. In a puzzle, the combination of a casing, 65 a tilting table mounted in said casing, a fence

on said table inclosing an inner portion and having an opening, objects adapted to move freely on said table and to pass through said opening, said table suitably shaped in its periphery to guide said objects along the wall 70 of said casing.

6. In a puzzle, the combination of a casing, a tilting table mounted in said casing, a fence on said table inclosing an inner portion and having an opening, objects adapted to move 75 freely on said table and to pass through said opening, a plurality of pairs of pivots on said table differently located relatively to the opening to permit the table to tilt in different directions relatively to said opening, means 80 for holding and supporting either of said pairs of pivots selectively, said table suitably shaped between said fence and said wall to guide said objects along the wall of said casing. 85

7. In a puzzle, the combination of a casing, a tilting table mounted in said casing, a fence on said table inclosing an inner portion and having openings on opposite sides, objects adapted to move freely on said table and to 90 pass through said openings, said table having a plurality of pairs of pivots, bearings adapted to selectively receive and support either pair of said pivots, said table suitably shaped between said fence and said wall to guide said objects along the wall of said casing. 95

8. In a puzzle, the combination of a casing, a tilting table mounted in said casing, a fence on said table inclosing an inner portion and having openings on opposite sides, objects adapted to move freely on said table and to pass through said openings, a plurality of pairs of pivots on said table differently located relatively to said openings, each of said pairs permitting said table to 100 tilt in a different direction relatively to the openings, a pair of bearings adapted to receive and support either of said pairs of pivots and a single pivot support for said 105 table permitting same to tilt in any direction, said table adapted to be supported either by said pairs of bearings or by said single support at will and suitably shaped between said fence and said wall to guide 110 said objects along the wall of said casing. 115

9. In a puzzle, the combination of a casing, a tilting table mounted in said casing, a fence on said table inclosing an inner portion and having openings, objects adapted to move freely on said table and to pass through 120 said openings, a plurality of pairs of pivots on said table differently located relatively to the openings, each of said pairs permitting said table to tilt in a different direction relatively to said openings, a pair of bearings 125 adapted to receive and support either of said pairs of pivots and a single pivot support for said table permitting same to tilt in any direction, said table adapted to be supported either by said pairs of bearings or by said 130

single support at will and suitably shaped between said fence and said wall to guide said objects along the wall of said casing.

10. In a puzzle, the combination of a casing, a tilting table pivotally supported therein, a fence on said table inclosing an inner portion and having oppositely disposed openings, objects adapted to move freely on said

table and to pass through said openings, the tilting of said table being controlled by the weight of said objects upon tilting of said casing.
